(57) **CLAIM**

The ornamental design for detachable kitchen shears, as shown and described.

DESCRIPTION

FIG. 1 is a front view of detachable kitchen shears showing our new design;

FIG. 2 is a top plan view of the detachable kitchen shears, the bottom plan view being identical thereto;

FIG. 3 is a left side view of the detachable kitchen shears of FIG. 1;

FIG. 4 is a right side view of the detachable kitchen shears of FIG. 1;

FIG. 5 is a rear view of the detachable kitchen shears of FIG. 1;

FIG. 6 is a front view of the detachable kitchen shears of FIG. 1 in an open position; and,

FIG. 7 is a perspective view of the detachable kitchen shears of FIG. 1.

The broken lines shown in the figures are for illustrative purposes only and form no part of the claimed design.
